(57) **CLAIM**

The ornamental design for a bicycle hook as shown and described.

DESCRIPTION

FIG. 1 is a front, right, top perspective view of a bicycle hook showing our new design;
FIG. 2 is a front view thereof;
FIG. 3 is a back view thereof;
FIG. 4 is a top view thereof;
FIG. 5 is a bottom view thereof;

(Continued)

FIG. 6 is an enlarged right view thereof; and,
FIG. 7 is an enlarged left view thereof.
The broken lines shown on the drawings depict portions of
the bicycle hook that form no part of the claimed design.
